UNITED STATES PATENT OFFICE.

WARWICK W. WOOD, OF WINSTON, NORTH CAROLINA.

DESIGN FOR A TOBACCO PLUG.

SPECIFICATION forming part of Design No. 21,992, dated November 15, 1892.

Application filed October 6, 1892. Serial No. 448,057. Term of patent 14 years.

To all whom it may concern:

Be it known that I, WARWICK W. WOOD, a citizen of the United States, residing at Winston, in the county of Forsyth and State 5 of North Carolina, have invented and produced a new and original Design for Plug-Tobacco; and I do hereby declare the following to be a full, clear, and exact description of the same, reference being had to the accompanying drawings, forming a part thereof.

Figure 1 is a front elevation of a plug of tobacco, showing three panels, each provided with a central field *in intaglio* and inclosed by two outer concentric rings in cameo and forming a frame or border. Fig. 2 shows an elevation of the back of the plug, showing the center field in cameo and inclosed by two concentric rings *in intaglio*; and Fig. 3 is a transverse section of Fig. 1 through a single 15 panel.

My design is for a plug of tobacco, and is

intended to present to the eye a picture-frame, the center field adapted to receive a picture, label, tag, or other suitable matter and inclosed by a raised frame or border. 25

The leading feature of my design for the plug consists of a rectangular panel having a depressed center field *a* and a raised frame or border *b*. On the back of the plug there are the same configurations; but the center 30 field is raised and the inclosing frame depressed, the whole being within the rectangular outline of the plug.

What I claim is—

The design for a plug of tobacco, substantially as shown and described. 35

In testimony whereof I hereunto affix my signature in presence of two witnesses.

WARWICK W. WOOD.

Witnesses:

E. T. FENWICK,
C. SEVERANCE.
